Primary Examiner—Prabhakar Deshmukh*(74) Attorney, Agent, or Firm*—Barlow, Josephs & Holmes, Ltd.(57) **CLAIM**

The ornamental design for a disc jockey video game controller, as shown and described.

DESCRIPTION

FIG. 1 is a perspective view of a disc jockey video game controller showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The elements depicted in broken lines in the various figures are included for environmental purposes only, and form no part of the claimed design.

The broken lines environment is for illustrative purpose and forms no part of the claimed design.
